UNITED STATES PATENT OFFICE.

EDWARD R. WILLIAMS, OF SHARPSBURG, PENNSYLVANIA.

DISPENSING DEVICE

1,392,379.

Specification of Letters Patent.

Patented Oct. 4, 1921.

Application filed March 23, 1917. Serial No. 156,926.

To all whom it may concern:

Be it known that I, EDWARD R. WILLIAMS, citizen of the United States, residing at Sharpsburg, in the county of Allegheny 5 and State of Pennsylvania, have invented certain new and useful Improvements in Dispensing Devices, of which the following is a specification.

This invention relates to devices for dispensing liquids, and more particularly to hand operated devices for dispensing liquids in regulated amounts. The object of the invention is to provide an improved device of the character stated which protects the liquid 10 from contamination, either by the hands or from outside sources, and which enables any desired amount of liquid to be withdrawn as required and discharged upon the hand of the operator. A further object of the invention is to provide a simple form of liquid dispensing device whose liquid supply is readily replenished, which can be easily manipulated, which may be so constructed as to constantly indicate the supply of liquid 15 therein, and which may be made in a wide variety of forms. Another object of the invention is to prevent the formation of a residual drop on the end of the spout, such as might dry or harden thereon and which is 20 either objectionable for that reason or because of being unsanitary. Further objects of the invention are to generally improve the construction of liquid dispensers of this type.

35 The invention comprises the construction and arrangement of parts hereinafter described and claimed.

In the drawings Figure 1, represents a front elevation of one form of device embodying the invention, the lower reservoir being broken out to expose interior parts; Fig. 2 is a plan view, the upper reservoir being omitted; Fig. 3 is a detail sectional elevation on the line 3-3, Fig. 2, looking 40 in the direction of the arrows; Fig. 4 is a section on the line 4-4, Fig. 2, showing the upper reservoir in place; Fig. 5 is a cross section on the line 5-5, Fig. 2, and showing a modification; Fig. 6 is a detail sectional view showing still another modification; Fig. 7 is a cross section on the line 7-7, Fig. 6; and Fig. 8 is a detail sectional view showing a modification.

The dispenser shown in the drawings com-

prises a main body portion 1, which may be 55 of any suitable shape of form and is shown as a substantially rectangular box with an open top, a front wall 2, a rear wall 3 and two side walls 4, with a bottom 5 in which is an opening 6 for a purpose which will 60 appear. The body 1 may be suitably arranged for attachment to any support and is shown as provided with one or several perforated ears 7 to receive screws threaded 65 into said support, although any construction for this purpose may be utilized. Below the body 1 is a liquid holding vessel 12 which may be threaded, soldered or otherwise secured to the body so as to form a tight joint therewith, as at 12^a, Fig. 8, in 70 which case the hollow body 1 forms a continuation of the liquid holding vessel and increases its capacity. This however is not essential. In the form shown in Fig. 1, the bottom 5 of the body is extended out beyond 75 the front wall to form a shelf or ledge 8, the under surface of said shelf and the bottom 5 being provided with concentric ribs 9 forming a channel 10 to receive the upper edge 11 of the liquid holding vessel 12. 80 The inner rib 9 is also provided with depending ears 13 to receive screws 14 which may be adjusted radially outwardly to secure and hold the vessel 12 in place. These screws may be manipulated by inserting the 85 fingers through the open top and the bottom hole 6 in the body.

The vessel 12 may be made of any suitable material, such as metal or the like, but is preferably made of glass or other 90 transparent material, so as to visibly indicate to the operator the quantity of liquid therein. The body 1 also serves as a support for the devices for discharging or dispensing liquid in desired amounts from the 95 vessel 12. As shown the front wall 2 of said body is provided on its inner face, above the opening 6 with a hollow cylindrical boss 15, of fairly large diameter, in which is located a small tube 16 of lesser diameter 100 whose lower end depends below the floor 5 and is provided with a packing or bushing 17. Said tube extends through the upper end of the boss 15 and laterally along the inner face of wall 2, and thence through 105 said wall 2 to form a spout 18 projecting forwardly and downwardly from the front of the body and out over the ledge 8 there-

of. Preferably said spout terminates a little to the left and above a finger hold or projection 19, for a purpose which will appear.

The ledge 8 serves as a support for an upright, hollow cylinder 20 provided at its upper end with a threaded cap 21 through which slides a plunger 22 having an operating head 23 on its exposed end. Within the cylinder is a spiral compression spring 24 engaging a rigid collar 25 on the rod 22. Said spring consequently always exerts a tendency to raise the rod when said rod is depressed by pressing with the thumb on the head 23. The lower end of rod 22 extends through the ledge or shelf 8 and within the vessel 12, where it is pivotally connected to one arm 26 of a lever pivoted at 27 to a stationary support, and whose other arm 28 is operatively connected to a pressure tube 29. Said tube slides within and is guided by the cylindrical bore of the boss 15 and also slides upon the packing or bushing 17 at the lower end of pipe 16. Tube 29 may also be provided with a suitable hole or opening above the packing 17 to serve as a vent for any liquid that may reach the space in boss 15 and tube 29 above said packing. As shown in Fig. 4, the boss 15 is provided with a pin 15^a entering a longitudinal slot 15^b in the side wall of pressure tube 29, thereby also preventing rotation of the pressure tube in said boss. Slot 15^b will be as long as the greatest range of movement of tube 29 and will also serve as a vent for the purpose stated. This construction is not essential, as the ends of pins 31 may be bent toward each other, as at 31^a, Fig. 5, to prevent rotation of the tube.

In the particular arrangement shown in the drawings the lever arm 28 is formed to provide a yoke 30 surrounding the pressure tube and lying between two pairs of small pins 31 projecting from said tube. The tube has its lower end closed as at 32, while its upper end is open, and its side wall is provided with one or several, two being shown, of small holes 33.

In the normal position of the parts, at rest, rod 22 is elevated and pressure tube 29 is depressed, the holes 33 lying below the level A of liquid in vessel 12. Consequently liquid flows through said holes into the tube 29 and fills the same up to the level of liquid in the vessel. Packing 17 is a close fit in the pressure tube, so that when the rod 22 is depressed and tube 29 rises the first motion of said tube causes the small holes 33 to pass packing 17, after which the liquid in the tube is forced upwardly through the small pipe 16 and discharged from the nozzle 18. The operator usually grasps the finger hold 19 with the first finger of his right hand and presses on the button 23 with his thumb. Consequently the liquid is discharged upon the fingers of the hand or into the palm, de-

pending upon the angle to which the nozzle 18 is bent. When the button 23 is released the parts return to normal position and the suction produced by tube 29 draws back thereinto any liquid remaining in the pipe 16, thereby preventing formation of a residual drop upon the end of the spout. This prevents contamination of the next quantity of liquid discharged by foreign substances gathered by said drop.

The pivotal connection between rod 22 and the lever arm 26 is formed by a transverse slot 34 in the rod 22 receiving an end of lever 26, a small pivot pin 35 being passed through the rod and lever. Slot 34 may be made long enough so that two or more sets of holes may be provided for the pin 35, thereby producing more or less travel of the pressure tube 29 and varying the quantity of liquid discharged by a stroke of the rod 22.

As shown in Fig. 5 the open top of the body 1 may be closed by a suitable cover, such as a flanged plate 36 entering the top of the body and resting on shoulders 37 thereof. In this case the dispenser is filled by taking off the cover and introducing liquid into the vessel 12 through the opening 6. Preferably, however, suitable means is provided for automatically replenishing the supply of liquid in vessel 12 as liquid is withdrawn therefrom. In the arrangement shown in Figs. 1 and 4, vessel 12 serves as a main supply vessel from which the liquid is directly drawn by the dispensing devices, and the supply of liquid in said main vessel is replenished from a storage reservoir shown as a bottle 38 which is inverted and whose body rests upon the shoulder 37. The neck 39 of said bottle extends through the opening 6 into vessel 12 and terminates above the level of the holes 33 when tube 29 is depressed. A liquid seal is therefore formed at the level of the bottle mouth and this level of liquid is maintained as long as any liquid remains in the bottle 38.

Any suitable means may be provided for supporting or holding the bottle 38 in upright position and preventing it from being tipped to one side or the other. Usually the engagement of the bottle body with the walls of the body 1 will be sufficient for this purpose, but if desired a suitable jacket or cover may be attached to the body and completely surround the bottle, although this is not essential. One suitable arrangement for holding the bottle is shown in Figs. 6 and 7. In this case the bottle is of special form, having a rounded upper end 40 provided with a groove or channel 41, forming a seat to receive a wire bail 42 whose lower portions pass through grooves between ribs 43 on the body and whose ends 44 are bent laterally and sprung into holes in said body. The bottle can be removed by prying out

the ends of the bail from the holes in the body.

The dispenser described may be made in a wide variety of forms, the drawings showing several of said forms for purposes of illustration. It will be understood, however, that the dispenser is capable of considerable modification without departing from the spirit of the invention. The apparatus may 10 be used for dispensing any kind of liquid, such as toilet water, liquid soap or the like, and is also useful for dispensing holy water in use in certain Catholic rites. It may be used with or without the hollow storage bot- 15 tle 38, depending upon how frequently the device is to be used and the quantity of liquid necessary to keep it running for the proper period of time. The apparatus is of simple form, may be readily operated and 20 is not likely to get out of order in use.

What I claim is:—

1. Liquid dispensing apparatus, comprising a liquid holding vessel, a discharge pipe supported thereon, and a hollow cylinder 25 closed at its lower end and having a portion lying below and provided with a supply opening below the level of liquid in said vessel and being slidably connected to said pipe, whereby sliding movement of said cylinder 30 on said pipe dispenses liquid therethrough.

2. Liquid dispensing apparatus, comprising a liquid holding vessel, a discharge pipe, a hollow cylinder closed at its lower end and having a portion lying below and provided 35 with a supply opening below the level of liquid in said vessel and being slidably connected to said pipe, whereby sliding movement of said cylinder on said pipe dispenses liquid therethrough, said pipe extending up- 40 wardly above the level of liquid and over the edge of said vessel, and means operable from the outside of said vessel for actuating said cylinder.

3. Liquid dispensing apparatus, comprising a liquid holding vessel, a discharge pipe 45 supported thereon and leading from the inside to the outside thereof, and a hollow cylinder closed at its lower end and surrounding said pipe within said vessel, said cylinder being provided with means for admitting liquid thereto and being reciprocable on said pipe for dispensing liquid therethrough.

4. Liquid dispensing apparatus, comprising a liquid holding vessel, a discharge pipe 55 extending above the level of liquid in said vessel and over its edge, a hollow cylinder closed at its lower end and having sliding engagement with said pipe for dispensing liquid therethrough, said cylinder being pro- 60 vided with a port in its side wall for ad-

mitting liquid to said cylinder when in its lowest position, and means for operating said cylinder.

5. Liquid dispensing apparatus, comprising a hollow body adapted for connection to a support and having an opening in its bottom wall, a liquid holding vessel depending from said body, means supported by said body for supplying liquid to said vessel, and means carried by said body and extending through said opening and operable from the outside of said body for discharging liquid over the upper edge of said vessel. 65

6. Liquid dispensing apparatus, comprising a hollow body having an opening in its bottom wall, a liquid holding vessel depending from said body, means supported by said body and extending through said opening for supplying liquid to said vessel, and a reciprocating member supported by said body and depending within said vessel for discharging liquid over the edge thereof. 75

7. Liquid dispensing apparatus, comprising a hollow body having an opening in its bottom wall, a liquid holding vessel depending from said body, means supported by said body and extending through said opening for supplying liquid to said vessel, and a reciprocating member supported by said body and depending within said vessel for discharging liquid therefrom, and means located on said body above said vessel for operating said member. 85

8. Liquid dispensing apparatus, comprising a hollow body having an opening in its bottom wall, a liquid holding vessel depending from and detachably connected to said body, means carried by said body and operable from the outside thereof for discharging liquid from said vessel at a level above the same, and an inverted liquid container having a portion extending through the open bottom of said body into said vessel for replenishing the supply of liquid therein. 95

9. Liquid dispensing apparatus, comprising a hollow body having an opening in its bottom wall, a liquid holding vessel depending from and detachably connected to said body, means carried by said body and operable from the outside thereof for discharging liquid from said vessel at a level above the same, and an inverted liquid container having a portion extending through the open bottom of said body into said vessel for replenishing the supply of liquid therein, 100 said discharging means depending within said vessel and body at one side of said container. 110

In testimony whereof I affix my signature.
EDWARD R. WILLIAMS.
